CLAIM

The ornamental design for a pelvic floor training device, as shown and described.

DESCRIPTION

1. Pelvic floor training device

Figure 1.1 is a perspective view of a pelvic floor training device;

Figure 1.2 is a right view thereof;

Figure 1.3 is a bottom view thereof;

Figure 1.4 is a top view thereof; and

Figure 1.5 is a front view thereof;

Figure 1.6 is a back view thereof; and

Figure 1.7 is a exploded view thereof.
